DESIGN FOR A CAN PIERCING IMPLEMENT

Paul C. Bye, Pasadena, Calif.

Application February 21, 1944, Serial No. 112,651

Term of patent 7 years

(Cl. D22—2)

To all whom it may concern:

Be it known that I, Paul C. Bye, a citizen of the United States, residing at Pasadena, in the county of Los Angeles and State of California, have invented a new, original, and ornamental Design for a Can Piercing Implement, of which the following is a specification, reference being had to the accompanying drawing, wherein:

Fig. 1 is an elevational view of a can piercing implement showing my new design;

Fig. 2 is a top plan view of the can piercing implement;

Fig. 3 is a bottom plan view of the can piercing implement, and

Fig. 4 is a section taken on line 4—4, Fig. 1.

I claim:

The ornamental design for a can piercing implement, as shown.

PAUL C. BYE.
